UNITED STATES PATENT OFFICE.

PETER BANFF, OF CHICAGO, ILLINOIS.

ANTISEPTIC ADHESIVE TAPE.

Application filed November 16, 1925. Serial No. 69,396.

This invention relates to an antiseptic adhesive tape and has for its object to provide, in a manner as hereinafter set forth, a tape of the class referred to, capable of being handled in an absolutely sanitary manner when applied.

A further object of the invention is to provide, in a manner as hereinafter set forth, a tape of the class referred to, with a medicated element and with means to prevent such element from becoming wet, damp or dislodged after the tape has been applied.

A further object of the invention is to provide, in a manner as hereinafter set forth, a tape of the class referred to, with a medicated element and with means for protecting such element when the tape is not in use.

A further object of the invention is to provide, in a manner as hereinafter set forth, a tape of the class referred to, whereby it can be made up in rolls or other forms without the surface thereof sticking together and further to retain the medicinal qualities thereof until applied.

Further objects of the invention are to provide, in a manner as hereinafter set forth, an antiseptic adhesive tape, which is comparatively simple in its construction and arrangement, durable, compact strong, thoroughly efficient in its use, conveniently applied, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be had which will come within the scope of the claims hereunto appended.

In the drawings wherein like reference characters denote corresponding parts throughout the several views:—

Figure 1 illustrates in perspective a length of antiseptic adhesive tape, in accordance with this invention, with the wrapper therefor removed and with one of the protecting elements for the medicated element lifted therefrom.

Figure 2 is a cross sectional view of an antiseptic adhesive tape, in accordance with this invention, having the wrapper therefor thereon.

Figure 3 is a cross sectional view of an

antiseptic adhesive tape, in accordance with this invention, with the wrapper removed and with each of the protecting elements for the medicated element shifted off the latter.

An antiseptic adhesive tape, in accordance with this invention, comprises a flexible web 1 of any suitable impervious material having an adhesive substance throughout the upper face 2 thereof. The lower face 3 of the web 1 is non-adhesive. The web 1 can be of any desirable length and width.

Secured to the upper face of the web 1, by the adhesive substance on said upper face and at the longitudinal center of the web 1 is a medicated element 4 which can be formed from any suitable flexible material folded or non-folded and provided with a suitable medicament. As by way of example, the element 4 is illustrated as formed from light gauze material folded to provide a series of interengaging lengthwise extending folds 5, 6 and 7 of equal width. The fold 7 is secured to the web 1 by the adhesive substance on the upper face thereof. The element 4 is of materially less width than the width of the web 1 and is so disposed with respect to the upper face of the web 1 as to be positioned equi-distant from each side edge of the web. The element 4 extends throughout the length of the web 1.

Secured to the upper face of the web 1, at each side of the element 4, is a removable protecting element and the said protecting elements are indicated generally by the reference character 8. Each of the protecting elements is of less width than the width of the web 1 and has a portion of its width, as indicated at 9, removably secured to the upper face of the web 1 and the portion 9 has its edge flush with the side edge of the web 1. That portion of the element 8, which is removably secured to the web 1, is of less width than that portion 10 of the element 8 which is not secured to the web 1. The secured portion 9 of the element 8 is spaced from the side of the element 4.

The portions 10 of the protecting elements 8, when in protecting position with respect to the element 4, are arranged to overlap each other as shown in Figure 2 and with the portion 10 of one of the elements seated on the top of the element 4. The disconnected portions 10 of the elements 8 permit of the same being readily grasped and removed from the web 4 when it is desired to use the web 1 and element

4. When the elements 8 are removed, the adhesive material which is exposed is utilized to secure the web to a person whereby the medicated element 4 will be retained in 5 position, and owing to the fact that the web 1 is of impervious material it prevents the element 4 from becoming wet or damp after having been applied, thus enabling the use of the tape, or if the tape is of plaster 10 form, in water and under damp conditions. The protecting elements 8, which are constructed from any suitable material, such as gauze, are so attached to the web 1 at each side of the element 4 that the tape 15 can be handled in an absolutely sanitary manner as it is unnecessary at any time to come in contact with the element 4.

A covering is provided for the web 1 and elements 8 and which consists of a web of 20 wax or paraffin paper or other material indicated at 11, and which is arranged in the manner as shown in Figure 2 and which is to completely envelope the web 1 and elements 8 when these latter are in protective 25 position with respect to the element 4. The elements 8, in connection with the covering 11, enable the tape to be made up in rolls or put up in any other form without the surfaces thereof sticking together and further the covering material assists to retain 30 the medicinal qualities of the element 4 until the tape is applied.

It is thought the many advantages of an 35 antiseptic adhesive tape, in accordance with this invention, can be readily understood, and although the preferred embodiment of the invention is as illustrated and described, yet it is to be understood that changes in the details of construction can be had which 40 will fall within the scope of the invention as claimed.

What I claim is:—

1. An antiseptic adhesive tape comprising an impervious web of appropriate width 45 having one face thereof provided throughout with an adhesive substance and its other face non-adhesive throughout, a lengthwise extending folded medicated element secured to said web by the adhesive coating and coextensive with said web, said element of materially less width than the width of the web and spaced equi-distant from each side edge 50 of the latter, and a pair of removable, oppositely extending protecting elements for said 55 adhesive coating and said medicated element,

each of said protecting elements having its outer side edge flush with the side edge of said web and its inner face at the outer portion thereof removably secured throughout to the adhesive face of the web at one side of the medicated element to provide a normally connected outer portion and a permanently disconnected inner portion, said protecting elements when removed exposing portions of said adhesive face to permit of said portions anchoring the web to retain the medicated element in position, said protecting elements having the inner portions thereof extending in opposite directions, normally overlapping each other, disconnected from each other, opposing and providing oppositely disposed finger grips for removing said protecting elements.

2. An antiseptic adhesive tape comprising 75 an impervious web of appropriate width having one face thereof provided with an adhesive substance and its other face non-adhesive throughout, a lengthwise extending medicated element secured to said web 80 by the adhesive coating and coextensive with said web, said element of materially less width than the width of the web and spaced from each side edge of the latter, a pair of removable, oppositely extending 85 protecting elements for said adhesive coating and said medicated element, each of said protecting elements having its inner face at the outer portion thereof removably secured throughout to the adhesive face of the web 90 at one side of the medicated element to provide a normally connected outer portion and a permanently disconnected inner portion, said protecting elements when removed exposing portions of said adhesive face to 95 permit of said portions anchoring the web to retain the medicated element in position, said protecting elements having the inner portions thereof extending in opposite directions, normally overlapping each other, disconnected from each other, opposing and providing oppositely disposed finger grips for removing said protecting elements, and each of said protecting elements of a 100 width materially greater than the width of said medicated element.

In testimony whereof, I affix my signature hereto.

PETER BANFF.
